(57) **CLAIM**

The ornamental design for a spraying module for composition, as shown and described.

DESCRIPTION

FIG. 1 is a perspective view of a spraying module for composition according to the new design.

FIG. 2 is a front view of the spraying module for composition of FIG. 1.

FIG. 3 is a rear view of the spraying module for composition of FIG. 1.

FIG. 4 is a left side view of the spraying module for composition of FIG. 1.

FIG. 5 is a right side view of the spraying module for composition of FIG. 1.

FIG. 6 is a top plan view of the spraying module for composition of FIG. 1.

FIG. 7 is a bottom plan view of the spraying module for composition of FIG. 1.

FIG. 8 is a perspective view of the spraying module for composition shown in an exploded environment of use with a guard and a main body of a cosmetic device; and,

FIG. 9 is a perspective view of the spraying module for composition shown in an environment of use with guard and a main body of a cosmetic device.

The broken lines illustrate portions of the spraying module for composition and form no part of the claimed design. The dot-dash broken lines in the drawings represent boundary lines and form no part of the claimed design.
